UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

OUTLET-FIXTURE.

1,126,267.

Specification of Letters Patent. Patented Jan. 26, 1915.

Application filed August 2, 1909. Serial No. 610,835

To all whom it may concern:

Be it known that I, HENRY T. PAISTE, a citizen of the United States, residing in Philadelphia, Pennsylvania, have invented 5 certain Improvements in Outlet-Fixtures, of which the following is a specification.

One object of my invention is to provide means whereby various forms of electrical apparatus such as switches, lamp bases, etc., 10 may be quickly and conveniently attached to or removed from an outlet fixture which may be mounted between a conduit or current conductors and such apparatus; it being further desired that the construction 15 shall be such as will permit a relatively wide range of adjustability in order that switches, lamp bases, etc., of various sizes may be connected to outlet fixtures without necessitating the use of more than one attaching device for all sizes.

I further desire to provide means for connecting electrical apparatus to an outlet fixture, which shall be of an extremely simple nature and easily adjustable to fit various sizes of apparatus.

These objects and other advantageous ends I secure as hereinafter set forth, reference being had to the accompanying drawings, in which:—

30 Figure 1, is a side elevation, partly in vertical section, illustrating my invention as employed to connect a switch with an outlet fixture; Fig. 2, is a perspective view of the outlet fixture showing the holding bar in position therein; Fig. 3, is an inverted perspective view of a switch base showing the holding bar connected thereto; and Fig. 4, is a perspective view of the holding bar.

In the above drawings, 1 represents an 40 outlet fixture, which in the present instance has the shape of a flat hollow cylinder open on one face and on the other having a transverse opening 2 for the reception of an electrical conductor-carrying conduit.

45 The open end of the fixture has inwardly projecting flanges 3, which, however, are cut away at two points 4 to permit of the insertion of a transverse holding bar 5 under them. This holding bar, which is preferably constructed as shown in Fig. 4, is in the present instance made of flat metal having at each end any desired number of threaded holes 6, in the present instance four; all of the holes at one end being at

different distances from the center of said bar 5.

The bar itself is mounted on a piece of electrical apparatus to be connected to the outlet fixture, which in the present instance is a switch having a body inclosed by a 60 casing 7, a base 8, and an operating button 9. The base has two holes through which extend screws 10, and these screws enter certain of the holes 6 at the ends of the cross bar.

65 As will be understood by those skilled in the art, all standard apparatus such as switches, lamp bases, etc., are provided with holes such as those through which the screws 10 pass, and the holes 6 in the holding bar 70 or plate are therefore so positioned that there shall always be one pair available for the reception of the screws 10 of the apparatus to be attached to the outlet fixture 1.

In assembling the various parts, I first 75 loosely attach the holding bar 5 to the base 8 by means of the screws 10 which are operable from the outside of the switch, though normally concealed by the casing 7, the adjustment being such that said bar depends 80 below the bottom of the base for a distance slightly greater than the thickness of the flange 3 of the outlet fixture. The switch or other electrical device is then applied to the fixture so that the holding bar 5, which 85 is made of the proper length, passes into its hollow interior; its ends entering through the openings 4 in said flange. The switch is then turned at an angle of say 45° so that the ends of the holding bar 5 are under the 90 flanges 3, after which the screws 10 are set up with a screw driver, thereby drawing the holding bar tightly against the under side of the flanges and rigidly connecting the switch to the outlet fixture. By loosening the 95 screws, and turning the switch on the base through an angle of 45°, the ends of the holding bar 5 may be again brought into the opening 4, after which the switch may be removed from the outlet fixture. I prefer- 100 ably so place the openings 4 in the flange 3 that the holding bar may be entered into the outlet fixture and turned through the proper angle to maintain it in position without interfering with any conductors which 105 may extend through said fixture.

I claim:—

1. The combination of an outlet fixture

having a flanged opening provided with two opposed recesses in its flange; a device to be connected to said fixture; a single holding bar of greater length than the diameter of the flanged opening of the fixture but sufficiently short to pass through the recesses of the flange into the interior thereof; with screws operable from the outside of the apparatus and threaded into the bar to hold the same in clamping engagement with the flange of the fixture.

2. The combination of an outlet fixture having a flanged opening provided with two opposite recesses in its flange; an electrical device; an integral holding bar of greater length than the diameter of the opening but

sufficiently short to pass through the recesses in the flange of said fixture; and screws operable outside the device for connecting it to said bar and to the outlet fixture, the bar being independent of the electrical circuit of the electrical device and freely movable in the outlet fixture when said screws are slack.

In testimony whereof, I have signed my name to this specification, in the presence of two subscribing witnesses.

HENRY T. PAISTE.
